UNITED STATES PATENT OFFICE.

ANDREW F. FOANS, OF NEW YORK, N. Y.

SIGN.

SPECIFICATION forming part of Letters Patent No. 378,198, dated February 21, 1888.

Application filed January 5, 1888. Serial No. 259,864. (No model.)

To all whom it may concern:

Be it known that I, ANDREW F. FOANS, of the city, county, and State of New York, have invented a new and Improved Sign, of which 5 the following is a full, clear, and exact description.

Reference is to be had to the accompanying drawings, forming a part of this specification, in which similar letters of reference indicate 10 corresponding parts in all the figures.

Figure 1 is a front elevation of my new and improved sign. Fig. 2 is a rear elevation of the same, the back board being removed; and Fig. 3 is a transverse sectional elevation of the 15 same, taken on the line $x-x$ of Fig. 1.

My invention consists of a sign wherein the letters are each attached to a bent and counterweighted rod journaled in a board or other support, so that the motion, jar, or tremble of 20 a car, stage, or other public conveyance will set the letters in motion to attract public attention.

A represents the main frame of the sign, in which is fitted the support B, a short distance 25 back of the glass front C. The letters D of the sign are held in front of the support B by the bent rods E, one for each letter. The rods E are journaled in small holes a, made in the support B, and said rods are each bent 30 downward back of the support B and counterweighted at their lower ends by weights b. (Shown in Figs. 2 and 3.) The wires E, where they pass through the support B, are bent to form the horizontal portions c, and in front of 35 this said wires are bent downward to form small cranks d, to which the letters are at-

tached, so that any movement of the rods E will swing the letters bodily, as indicated in dotted lines in Figs. 1 and 2. In the holes a are fitted small metal tubes f, which serve as 40 metal bearings for the rods E, and also serve to swing the letters D and weights b clear of the surfaces of the support B.

Having thus fully described my invention, I claim as new and desire to secure by Letters 45 Patent—

1. In a sign, the combination, with a support, B, of the bent counterweighted rods E, journaled in the support, and to which the letters are attached, substantially as and for 50 the purposes described.

2. The sign herein shown and described, the same consisting of the support B, letters D, and rods E, journaled in said support, one end of each rod being counterweighted, the other 55 being bent to form a crank, d, to which the letter is attached, substantially as described.

3. In a sign, the rods E, counterweighted at one end and bent to form the horizontal portion c, in combination with the letters D 50 and support B, in which the rods are journaled, substantially as shown and described.

4. In a sign, the support B, formed with orifices a, in which are fitted the tubes f, in combination with the bent and counterweighted rods E, journaled in said tubes, and the letters D, secured to the rods, substantially as described.

ANDREW F. FOANS.
